Chas. H. Clark.

By E. B. Whitmore, Atty.

UNITED STATES PATENT OFFICE.

CHARLES H. CLARK, OF ROCHESTER, NEW YORK.

LAMP-WICK TRIMMER.

SPECIFICATION forming part of Letters Patent No. 247,888, dated October 4, 1881.

Application filed August 22, 1881. (No model.)

To all whom it may concern:

Be it known that I, CHARLES H. CLARK, of Rochester, in the county of Monroe and State of New York, have invented a new and useful Improvement in Lamp-Wick Trimmers, which improvement is fully set forth in the following specification and accompanying drawings.

The object of my invention is to produce an implement for removing the charred part from the wicks of lamps and evenly and conveniently trimming said wicks of kerosene and other lamps; and it consists of parts and devices described in the following specification, and more particularly pointed out in the claims.

Referring to the drawings, Figure 1 is a plan of my newly-invented wick-trimmer; Fig. 2, a side elevation of the same. Fig. 3 is a detached view, showing a part in section, and showing more clearly the relation of certain parts; and Fig. 4 shows a modification in the formation of the parts there shown.

A and B in the figures are two levers mutually fulcrumed at the pivot *a*, and provided respectively with finger and thumb rests *h* and *k*, designed to be operated by the thumb and fingers of the hand in a manner similar to that in which the levers of a pair of ordinary shears are operated. These levers, at the ends opposite the finger-rests, terminate in hollow parts or spoons C and D, each having a straight side opposite the other, and in using the device the said straight parts or sides are pressed upon the sides of the lamp-wick *b*, grasping the same firmly between them, as shown. The lever B is composed in part of a flat spring, *d*, secured at one end to the extremity of the spoon-piece C and at the other to the part *f* of the lever, which spring yields to the pressure of the thumb upon the rest *k*, if continued after the spoons have commenced to press upon the sides of the wick, as above stated, this said continued pressure of the thumb carrying the part *f* of the lever B farther over toward the opposing lever A.

g is a device for acting upon or trimming the wick, being preferably some suitable style of stiff brush, held by a rod, *c*, to the part *f* of the lever B, said trimmer or brush *g* resting normally over the spoon C, as shown in Fig. 1. Now, if the lever B be pressed by the thumb, as above described, after the spoons have seized

the wick the brush *g* will be carried horizontally across the end of the wick *b* to a corresponding position over the other spoon, D. (Shown in dotted lines.) By partially removing the pressure of the thumb the spring, by 55 its elasticity, will again carry the brush back across the wick to its normal position over the spoon C. This repeated passing of the brush across the end of the wick is designed to remove the charred portion thereof, depositing 60 the same in the receptacles or spoons C D. As shown in Fig. 3, the straight parts or inner edges of the spoons, where they come in contact with the wick, are provided with equal upturned flanges or lips *e e*, made slightly curved 65 or crowning at their upper edges, and the wires or bristles of the brush sweep across the convex edges of said lips when the brush is operated as above described.

In using the implement the wick to be trimmed 70 is seized by the spoons in such a manner that the charred portion of the same appears just above the lips *e e*, as shown, to be removed by the operation of the brush, as above stated. The crowning of the lips gives to the end of 75 the trimmed wick such a shape as to secure for the flame the most desirable shape or outline, and the shape of the lips may be changed as desired.

It will be observed that no motion of the levers A B about the pivot *a* will cause the brush to change its position relatively to that of the spoon C. Only the yielding of the spring *d* by a pressure at *k* will cause the brush to move from its normal position, and the brush in no 80 case can pass outside of the spoons.

Fig. 4 shows a modification in the form of the lever B, in which a joint, *s*, is introduced and an expanding-spring, *t*, used to open the levers.

In use the bottom surface of the spoons may 90 be rested upon the upper end of the wick-tube *l*, as shown in Fig. 3.

I claim as my invention—

1. The trimming device *g* for lamp-wicks, in combination with the spoons or parts C D, designed to hold the wick while being trimmed, said device *g* being caused to act upon the wick by means of the yielding lever B, substantially as shown and described.

2. The lever A, provided with the spoon- 100

shaped part D, and the opposing lever B, consisting in part of the spoon C and spring d, said levers being mutually fulcrumed and acting conjointly, in combination with a brush g, 5 substantially as shown.

3. In combination with the trimming device or brush g, spoons C and D, provided with pro-

jections or lips e e, substantially as and for the purpose set forth.

CHAS. H. CLARK.
